Patented July 3, 1917.

UNITED STATES PATENT OFFICE.

HENRY H. CUTLER, OF MILWAUKEE, WISCONSIN, ASSIGNOR TO THE CUTLER-HAMMER MFG. CO., OF MILWAUKEE, WISCONSIN, A CORPORATION OF WISCONSIN.

STARTING DEVICE FOR MULTIPHASE MOTORS.

1,231,714.

Specification of Letters Patent.

Patented July 3, 1917.

Application filed November 9, 1906, Serial No. 342,914. Renewed November 2, 1916. Serial No. 129,232.

To all whom it may concern:

Be it known that I, HENRY H. CUTLER, a citizen of the United States, residing at Milwaukee, in the county of Milwaukee and State of Wisconsin, have invented new and useful Improvements in Starting Devices for Multiphase Motors, of which the following is a full, clear, concise, and exact description, reference being had to the accompanying drawing, forming a part of this specification.

My invention relates to improvements in starting devices for multiphase motors.

One of the objects of my invention is to provide means for removing resistance from the motor circuit in such a manner that the motor will gradually increase in speed without undue strain upon the motor or power circuit. I have illustrated in the accompanying Figure 1 a diagrammatic view of one of the circuit arrangements for the purpose of disclosing my invention.

In Fig. 2 I have shown an end view of the drum and ratchet arrangement hereinafter to be described.

In the drawing, I have illustrated the rotor 2 of a three-phase alternating current motor provided with the three sets of resistances 3, 4, and 5. Each set of resistance is connected with a collector ring on the rotor of the motor, and is divided into sections. The sections of each set of resistance are connected with sets 6, 7 and 8 of contact fingers, which are arranged to be engaged by sets of contacts 9, 10 and 11 mounted upon a drum 12. I have illustrated in the diagrammatic view of the drawing the various contacts as being electrically connected by wire conductors, but in practice, I preferably construct the drum of iron or other conducting material and provide the same with projections upon which are fastened the contacts, the drum in this case serving to electrically connect the contacts instead of special conductors as illustrated in the drawing.

At the extreme right of the drum a contact segment 13 is provided which is insulated from the drum and extends clear around the same. I have illustrated in the drawing the insulated material as being interposed between the end of the drum and the body thereof, but any manner of insula-

ing the contact segment 13 from the drum may be utilized in practice. 55

Arranged to contact with the segment 13 which is of the peculiar construction illustrated in the drawing, are a number of contact fingers 14, 15, 16 and 17 the purposes of which will appear more fully hereinafter. 60

For the purpose of rotating the drum, I have provided upon the end thereof a series of ratchet teeth 18 adapted to be engaged and operated by a ratchet 19 connected with the core of the solenoid 20. This is arranged to automatically make and break its own circuit, whereby the core will be alternately raised and lowered. For effecting this operation one terminal of the solenoid is connected by the conductor 21 with the movable 65 switch 22, the opposite end of which is arranged to engage a contact 23 connected by the conductor 24 with the finger 15. The opposite terminal of the solenoid is connected by conductors 25 and 26 with the 70 middle wire 28 of the supply wires 27, 28 and 29. The upper end of the core 30 of the solenoid 20 is provided with an extension 31 upon which are arranged a pair of adjustable nuts 32 and 33 which are arranged to engage the switch 22 to operate the same. The solenoid 20 is also provided with a shunt circuit 34 having arranged therein an adjustable resistance 35, which provides a path for the surge of current or 75 kick when the circuit thereof is broken. This surge being in the same direction as the energizing current maintains the magnet energized longer than if this paralleled path were omitted. By varying the resistance in 80 this path the time of deenergization may be varied and the rapidity of reciprocation of the core of the solenoid varied. 85

A pair of switches 36 and 37 control the circuit from the main line to the stator of 85 the motor. These switches are operated by a solenoid 39 having one terminal thereof connected by the conductor 40 through a main hand switch 41 with the middle conductor 28 of the main line. The opposite 100 terminal of the solenoid 39 is connected by conductor 42 with the first conductor 27 of the main line through the resistance 43 and is also connected by conductor 44 with the switch contact 17. One terminal of the 105 switch 36 is connected by conductor 45 with

the third wire 29 of the main line and the contact 43 of this switch is connected by the conductor 47 with the third terminal 48 of the stator of the motor. One terminal 5 of the switch 37 is connected by conductor 49 with the middle wire 28 of the main line and the contact 50 of said switch is connected by conductor 51 with the middle terminal 52 of the stator of the motor. The 10 first terminal 53 of the stator of the motor is connected by conductor 54 with the first wire 27 of the main line.

A relay device comprising a solenoid 55 and a contact member 56 carried by the core 15 thereof which is arranged to contact with the terminals 57 and 58 and 59 and 60, is arranged for controlling the circuit through the solenoid 39. One terminal of the solenoid 55 is connected by conductors 42* and 20 42 with the first wire 27 of the main line and the other terminal thereof is connected by conductor 40 and the hand switch 41 with the middle wire 28 of the main line. A branch conductor 61 also extends from 25 one terminal of the solenoid 55 to the terminal 58 and terminal 60 of the switch controlled by said solenoid. The terminal 57 of this switch is connected by conductor 62 with the contact finger 16 and the terminal 30 59 of the switch is connected by conductor 63 with the contact finger 14.

In operation, assuming that the contact fingers 15 to 17 are in engagement with the bottom of the contact segment 13, when the 35 main hand switch 41 is closed the circuit will be closed from the middle conductor of the main line through the conductor 40 through the winding of the solenoid 55 and thence by conductors 42* and 42 back to the first wire 27 of the main line. This energizes the solenoid causing it to raise its core and connect the terminals 57 and 58 by the contact 56. The circuit is thereupon closed through the winding of the 45 solenoid 20 from the middle wire 28 of the main line through conductors 26 and 25 through the winding of the solenoid by conductor 21 across the switch 22 by conductor 24 to the contact finger 15, across the contact segment 13 to the contact finger 16, thence by conductor 62 to terminal 57, across the contact 56 to terminal 58 and by conductors 61, 42* and 42 back to the first wire 27 of the main line. At the same time 50 the circuit is closed by way of conductors 26 and 40 through the winding of the solenoid 39 by conductor 44 to the contact finger 17 across the contact segment 13 to the contact finger 16, thence by conductor 62 across the terminals 57 and 58 by contact 56, and by wires 61, 42* and 42 to the first wire 27 of the main line. The solenoid 39 is thereby energized, closing the switches 36 and 37 which control the circuit through the stator 55 of the motor.

The solenoid 20 having been energized, will raise its core causing the ratchet 19 to engage the teeth 18 on the drum 12 and rotate the drum one step whereby the first of each of the sets of contacts 9, 10 and 11 70 will engage the first finger of each of the sets of fingers 3, 4 and 5. The motor will now operate with all of the resistance in the rotor circuit.

As the core 30 of the solenoid 20 is raised, the nut 33 will strike the switch arm 22 and open the circuit through the solehold which will permit its core to drop. As the core drops, the switch 22 again closes, closing the circuit through the solenoid and the solenoid 80 immediately raises its core, turning the drum another step, thereby short circuiting one section of the resistances 3, 4 and 5, and increasing the speed of the motor. At the same time the contact finger 17 will pass 85 off the portion 64 of the contact segment 13 and the circuit through the solenoid 39 instead of passing by way of contact fingers 16 and 17 will pass through the resistance 43, which so reduces the current passing 90 through the solenoid that while there is sufficient current to maintain the core of the solenoid raised there is not sufficient to raise the core in event the same is dropped. The operation of the core of the solenoid 20 continues to rotate the drum 12, cutting out 95 sections of the resistances 3, 4 and 5 until the last of the contacts 9, 10 and 11 are reached when the motor will be running at full speed with the starter in a full on position. When the last of the contacts 9, 10 and 11 is reached, the contact finger 16 will have passed off the section 65 of the contact segment 13, thereby opening the circuit of the reciprocating solenoid 20 and the solenoid 100 will remain at rest. In event now, the main switch 41 is opened to stop the motor, the solenoid 39 will be deenergized, dropping its core and thereby opening the switches 36 and 37 which control the circuit 105 of the stator of the motor and at the same time the circuit through the solenoid 55 will be opened, and its core will drop and open the circuit between the terminals 57 and 58. The dropping of the core of the solenoid 55, 110 however, will cause the contact 56 to engage the contacts 59 and 60 which immediately closes a circuit through the solenoid 20 by way of conductors 26 and 25 through the solenoid winding 20, conductor 21, switch 115 22, conductor 24, contact finger 15, contact finger 14, conductor 62, across the terminals 59 and 60 by way of conductor contact 66, conductors 61, 42* and 42, back to the first wire 27 of the main line. The solenoid thus being energized will raise its core and move the drum 12 another step and the contact finger 14 will move off the portion 66 of the contact segment 13, thereby opening the 120 circuit of the solenoid 20 but moving the 125 contact segment 13 to the position 64. The dropping of the core of the solenoid 55, 130 however, will cause the contact 56 to engage the contacts 59 and 60 which immediately closes a circuit through the solenoid 20 by way of conductors 26 and 25 through the solenoid winding 20, conductor 21, switch 22, conductor 24, contact finger 15, contact finger 14, conductor 62, across the terminals 59 and 60 by way of conductor contact 66, conductors 61, 42* and 42, back to the first wire 27 of the main line. The solenoid thus being energized will raise its core and move the drum 12 another step and the contact finger 14 will move off the portion 66 of the contact segment 13, thereby opening the circuit of the solenoid 20 but moving the 130 contact segment 13 to the position 64.

portion 67 of the contact segment 13 into engagement with the fingers 15, 16 and 17, whereby the device will be in a starting position, and will operate to start the motor 5 and perform the same operation as hereinbefore described upon the closing of the switch 41.

If the main switch 41 is opened before the drum has reached full on position the motor 10 will be stopped by the dropping of the core of the solenoid 39 and the solenoid 55 will be deenergized to permit its core to drop, but the contact 56 engaging terminals 59 and 60 will maintain the circuit through the solenoid 20 and it will continue to rotate the drum until the finger 14 moves off the section 66 of the segment 13 when the drum 15 will be in starting position. It will therefore be seen that no matter in what position the drum may be when the motor is stopped, it will always be moved to starting position 20 before the solenoid 20 ceases to operate.

Having described my invention what I claim as new and desire to secure by Letters 25 Patent is:

1. The combination with a multiphase motor, of resistance in the rotor circuit thereof, step by step switch mechanism for removing said resistance, electro-magnetic reciprocating means connected across the supply circuit for operating said step by step switch mechanism, and a relay connected in shunt of said electro-magnetic reciprocating means for controlling the circuit of said electro-magnetic reciprocating means.

2. The combination with a multiphase motor, of resistance in the rotor circuit thereof, step by step switch mechanism for removing said resistance, electro-magnetic reciprocating means connected across the supply circuit for operating said step by step switch mechanism, and a relay connected in shunt of said electro-magnetic reciprocating means and controlling the circuit of said electro-magnetic reciprocating means so that said step by step switch mechanism may be returned to its starting position whenever the motor is stopped.

3. The combination with a multiphase motor, of resistance in the rotor circuit thereof, a rotating drum, contact mechanism operated by the rotation of said drum for controlling said resistance, electro-magnetic reciprocating mechanism for operating said drum, an auxiliary contact segment carried by said drum, and contact members adapted to be engaged by said segment to control the circuit of said electro-magnetic reciprocating mechanism.

4. The combination with a motor, of a resistance in the circuit thereof, step by step switch mechanism for controlling said resistance, electro-magnetic reciprocating means for operating said step by step switch

mechanism, a relay, and an auxiliary step by step switch operated by said electro-magnetic reciprocating means and coöperating with said relay to control the circuit through said electro-magnetic reciprocating means. 70

5. The combination with a multiphase motor, of resistance in the rotor circuit thereof, a rotating contact drum for controlling said resistance, electro-magnetic reciprocating mechanism for rotating said drum, an auxiliary contact segment carried by said drum, and contact members arranged to be engaged by said contact segment to control the circuit of said electro-magnetic reciprocating mechanism so that said drum may be 75 moved to its initial position whenever the motor is stopped.

6. The combination with a motor, of resistance in the circuit thereof, a rotating contact drum for controlling said resistance, 85 electro-magnetic reciprocating mechanism for rotating said drum, an auxiliary contact segment carried by said drum, and contact members adapted to be engaged by said contact segment to control the circuit of said 90 electro-magnetic reciprocating mechanism.

7. The combination with a motor, of resistance in the circuit thereof, a rotating contact drum for controlling said resistance, electro-magnetic reciprocating mechanism for rotating said drum, an auxiliary contact segment carried by said drum, and contact members arranged to be engaged by said contact segment to control the circuit of said 95 electro-magnetic reciprocating mechanism so that said drum may be moved to its initial 100 position whenever the motor is stopped.

8. The combination with a multiphase motor, of resistance in the rotor circuit thereof, step by step switch mechanism for removing said resistance, electro-magnetic reciprocating mechanism for operating said step by step switch mechanism, auxiliary switch mechanism operating with said step by step switch mechanism for controlling the circuit 110 of said electro-magnetic reciprocating mechanism, and a relay controlling the circuit of the stator of said motor, the circuit of said relay being controlled by said auxiliary switch mechanism. 115

9. The combination with a multi-phase motor, of resistance therefor, a drum for controlling said resistance, means for operating said drum, an electromagnetic switch for controlling the stator circuit of 120 the motor, and a switch operated by said drum for controlling the circuit through said magnet.

10. The combination with a multiphase motor, of resistance in the rotor circuit thereof, a rotating contact drum for controlling said resistance, a periodically operated electro-magnet for rotating said drum step by step, an auxiliary contact segment carried by said drum, and contact members 125 130

- associated with said auxiliary contact segment whereby the circuit of said electromagnet is opened after it has rotated the drum one step beyond the full-on position, 5 after the motor has been stopped.
11. The combination with a motor, of a resistance in the rotor circuit thereof, a drum for controlling said resistance, a periodically operating electromagnet for rotating said drum step by step, a relay controlling the circuit through said magnet, and means for permitting said magnet to operate after the motor has been stopped, until the drum has been moved to its starting position.
12. The combination with a multi-phase motor, of resistance in the rotor circuit, a drum for controlling said resistance, a magnet for rotating said drum, a relay and a switch operated by said drum co-operating to control the circuit through said magnet.
13. The combination with a motor, of a resistance in the circuit thereof, step by step switch mechanism for controlling said resistance, a solenoid, a reciprocating core therefor connected with said step by step switch mechanism, and a variable resistance circuit in shunt of said solenoid.
14. The combination with a motor, of a resistance in the circuit thereof, step by step switch mechanism for controlling said resistance, electromagnetic reciprocating mechanism for operating said step by step mechanism, auxiliary switch contacts, and a common contact segment associated therewith and operating with the advance of said step by step switch mechanism for controlling the circuit of said electromagnetic reciprocating mechanism.
15. The combination with a motor, of a resistance in the circuit thereof, step by step switch mechanism for controlling said resistance, electromagnetic reciprocating mechanism for operating said step by step switch mechanism, auxiliary circuit changing mechanism operated with the advance of said step by step mechanism, a relay and a main switch therefor, said relay and said auxiliary circuit changing mechanism coacting to control the circuit of said reciprocating electromagnetic mechanism.
16. The combination with a motor, of a resistance in the circuit thereof, step by step switch mechanism controlling said resistance, electromagnet reciprocating mechanism for operating said step by step switch mechanism, a relay for controlling the circuit of said electromagnetic reciprocating mechanism, a main switch governing said relay and auxiliary circuit changing mechanism operating with the advance of said step by step switch mechanism, for opening the circuit of said electromagnetic reciprocating mechanism when said main switch is closed, after all of said resistance has been
- cut out of the circuit, and for maintaining the circuit of said electromagnetic reciprocating mechanism when said main switch is opened until said step by step switch mechanism has returned to its starting position. 70
17. The combination with a motor, of a resistance in the circuit of one element thereof, step by step switch mechanism for controlling said resistance, electromagnetic reciprocating mechanism for operating said step by step switch mechanism, a relay for controlling the circuit of said electromagnetic reciprocating mechanism, a main switch governing said relay, a relay controlling the circuit for the other element of the motor and governed by said main switch, and auxiliary circuit changing mechanism operating with the advance of said step by step switch mechanism, for opening the circuit of said electromagnetic reciprocating mechanism when said main switch is closed, after all of said resistance has been cut out of the circuit and for maintaining the circuit of said electromagnetic reciprocating mechanism when said main switch is open until the 80 step by step switch mechanism has returned to its starting position.
18. The combination with a motor, of a resistance in the circuit of one element thereof, step by step switch mechanism for controlling said resistance, a solenoid, a core therefor adapted when attracted to break the circuit of said solenoid and operatively connected with said step by step switch mechanism, a relay for controlling the circuit of 100 said solenoid, a main switch governing said relay, auxiliary circuit changing mechanism for opening the circuit of said solenoid when said main switch is closed, after all of said resistance has been removed from the circuit 105 and for maintaining the circuit of said solenoid when said main switch is open until said step by step switch mechanism has returned to its starting position.
19. The combination with a motor, of a resistance in the circuit of one element thereof, step by step switch mechanism for controlling said resistance, electromagnetic reciprocating mechanism for operating said step by step switch mechanism, a relay for 110 controlling the circuit of said electromagnetic reciprocating mechanism, a main switch governing said relay, auxiliary circuit changing mechanism for opening the circuit of said electromagnetic reciprocating mechanism, when said main switch is closed, after all of said resistance has been removed from the circuit and for maintaining the circuit of said electromagnetic reciprocating mechanism when said main 115 switch is open until said step by step switch mechanism has returned to its starting position, a cut-off relay for controlling the circuit through the other element of the motor, an auxiliary resistance in series with said 120
- 125
- 130

cut-off relay, and a circuit in shunt of said auxiliary resistance, said circuit being closed by said auxiliary circuit changing mechanism when said main switch is closed, and being opened thereby after said cut-off relay has been actuated.

20. The combination with an alternating current motor, of means for controlling the same including a primary circuit-closing device, an impedance for the secondary circuit, an electromagnetic device for gradually removing said impedance by a movement in one direction and connections established upon stopping of said motor whereby said device is energizable for continued movement in the same direction to reinsert impedance preparatory to restarting said motor.

21. The combination with a polyphase motor, of means controlling the same including a primary circuit-closing device, impedance for each phase of the secondary circuit, a controlling member for said impedance, an electromagnetic device for moving said member in the same direction to exclude and reinsert said impedance, a switch controlling said electromagnetic device to stop said member in a position to exclude said impedance and connections established upon interruption of the primary circuit of said motor to shunt said switch for continued movement of said member to reinsert impedance.

22. The combination with an electric motor, of means for establishing power connections therefor, a variable resistance for inclusion in circuit with said motor, an electromagnetic device for gradually removing said resistance by movement in one direction and connections established upon the stopping of said motor whereby said device is energizable for continued movement

in the same direction to reinsert said resistance preparatory to restarting said motor.

23. The combination with an electric motor, of means for establishing power connections therefor, a variable resistance for inclusion in circuit with said motor, a controlling member for said resistance, an electromagnetic device for moving said member in the same direction to exclude and reinsert said resistance, a switch controlling said device to stop said member in a position to exclude said resistance and connections established upon interruption of the power connections of said motor to shunt said switch for continued movement of said member to reinsert said resistance.

24. The combination with an electric motor, of electro-responsive means to establish power connections therefor, a variable resistance for inclusion in circuit with said motor, a member controlling said resistance and said electro-responsive means to insure against response of the latter except upon inclusion of the former in the motor circuit, an electromagnetic device for moving said member uni-directionally to exclude and reinsert said resistance, means controlling said device to stop said member in a position to exclude said resistance and means adapted upon interruption of the power connections of said motor to establish energizing connections for said device to reinsert said resistance.

In witness whereof, I have hereunto subscribed my name in the presence of two witnesses.
